UNITED STATES PATENT OFFICE.

GEORGE B. COOVER AND HERBERT A. BRUNER, OF LAMAR, COLORADO.

SUPPORTING MEANS FOR STEAM-PRESSING MACHINES.

Application filed May 6, 1922. Serial No. 553,973.

To all whom it may concern:

Be it known that we, GEORGE B. COOVER and HERBERT A. BRUNER, citizens of the United States, residing at Lamar, in the 5 county of Prowers and State of Colorado, have invented certain new and useful Improvements in Supporting Means for Steam-Pressing Machines, of which the following is a specification, reference being had to the 10 accompanying drawings.

This invention relates to steam pressing machines such as are used for pressing trousers, coats and other clothes, and particularly to the means for supporting the 15 clothes while they are being pressed.

In the ordinary pressing machine, the pad or cushion upon which the article is supported while being pressed by the "press head" is mounted upon a table at some distance above the table, as shown in the accompanying drawing, so that in pressing the leg of a pair of trousers, for instance, the upper portion of the trousers and the other leg will hang down upon the table and it is 20 impossible to press properly those portions of the trouser leg adjacent the crotch, and in pressing coats, and particularly the sleeves of coats, the body portion of the garment hangs down over one end of the support cushion and rests upon the table and it is 25 impossible to properly press the sleeve close to the junction of the sleeve with the body of the coat.

The general object of our invention is to 30 provide an attachment for ordinary steam clothes pressers of this character which will support the body of the article being pressed, which will permit the handling of the goods to be pressed in the most convenient manner 35 and allow the pressing to be done without any part of the garment hanging over and escaping being pressed, and furthermore allow the garment to be so pressed as to make uniform creases.

40 A further object is to provide an auxiliary table adapted to be supported upon the main table of the machine in a position of approximate alignment with the pressing cushion and upon which the body of the garment may rest while the legs or arms are being pressed, and further in this connection to make this auxiliary table foldable so that it may be put into compact form for storage 45 or shipment.

50 Another object is to provide a second auxiliary table coating with the first and with

the cushion to assist in supporting a trouser leg upon the cushion with the front crease of the trouser leg immediately beneath the middle of the cushion where the greatest 60 amount of pressure will come without any portion of the trouser leg hanging over the cushion and thus not being properly supported while pressing is being done.

Other objects will appear in the course of 65 the following description.

Our invention is illustrated in the accompanying drawings, wherein:—

Figure 1 is a perspective view showing a clothes pressing machine with our coat supporting member mounted thereon; 70

Figure 2 is a like view to Figure 1, but showing means for supporting a trouser leg while it is being pressed;

Figure 3 is an end elevation of the support 75 10 in Figure 1;

Figure 4 is an end elevation of the support after it is folded;

Figure 5 is a fragmentary sectional view 80 of the leg 22;

Figure 6 is an under side plan view of the support 10 with the legs folded;

Figure 7 is an elevation of the hinged leaves 15;

Figure 8 is a view of the hinged leaves 13; 85

Figure 9 is an under side view of the support 29, showing the crow foot 30.

Referring to these drawings, A designates the main table of a steam presser, such as commonly used in tailor shops, B the 90 bracket supporting the cushion C or buck, and D the press head which is hingedly supported over the cushion and which is adapted to be forced down upon the cushion and upon the garment being pressed. All 95 of these parts are of any ordinary and usual construction and form no part of our invention.

In conjunction with the cushion C, we provide an auxiliary table, designated 10, 100 which is preferably made in two sections a and b, and with a marginal flange or wall 11. At one end both sections a and b are cut away, as at 12, this cut being semi-circular in form so that when the table is 105 in place the curved end of the buck C will fit into this curved recess and rest upon the adjacent wall 11. The material of the auxiliary table 10 is preferably wood and preferably about 9/16" in thickness. The two 110 sections of the table top are hinged to each other by means of three members 13, 14 and

15. The members 14 and 15 are nearly alike. The member 13, however, is slightly different from the members 14 and 15 and constitutes a brace extending beneath the table 5 just forward of the semi-circular cut-out portion 12. This brace is necessary, as otherwise this semi-circular cut-out portion 12 would render the auxiliary table very weak at this point. This brace 13 is formed 10 of two sections of angle iron, as illustrated in Figure 8, each section being attached by one flange to the under side of the table top, the other flange extending vertically downward. This flange of each section is 15 relatively higher at the middle of the auxiliary table than at the end. These two flanges overlap each other, as illustrated in Figure 8, and are pivoted to each other by a rivet 16. The horizontal flanges of the two 20 sections 13 of the brace are inwardly turned at their adjacent ends, as at 17. Each section of the brace adjacent the pivot bolt 16 is cut away, as at 18. The two sections of the brace are held to the under side of the 25 table top by screws or in any other suitable manner. The end brace and hinge member 15, as illustrated in Figure 7, is also formed of two sections of angle iron which are attached by screws or otherwise to the under 30 face of the table top, these two sections of angle iron overlapping each other at their adjacent ends and being pivoted to each other by means of the rivet 19. The horizontal flanges are inwardly turned, as at 20, 35 and abut against each other when the two sections of the press are in alignment. The depending flange of each section of the press is formed adjacent its extremities with an opening 21 and disposed beneath the table 40 top are the two supports, designated generally 22, each support being formed of a rod or of a small channel iron formed to provide a longitudinally extending portion 23 disposed parallel to the under face of the 45 auxiliary table, the ends of each supporting member being recessed, as at 24, to receive screws, pivot pins or like members 25 and thus the supporting members may be turned from a horizontal position beneath the auxiliary 50 table to a vertical position to support the auxiliary table, as illustrated in Figure 1.

When turned into a horizontal position, the outer cross bars of the supporting member 55 will be received in the notches or recesses 18 of the middle brace 13. A brace 26 having an eye 27 at one end is pivoted by a bolt, rivet or the like to the depending flange of each hinge leaf or brace leaf 15. 60 The extremity of this brace 26 is angularly bent, as at 28, for engagement in a recess in the corresponding leg. When these angular ends of the braces are engaged with the legs, they will hold the legs in a vertical 65 position, but when released from the

legs they will permit the legs to be shifted to a horizontal position.

It is obvious that with this construction the auxiliary table may be folded up for storage or shipment, the legs being between 70 the two sections of the auxiliary table and closed thereby, or the auxiliary table may be turned out to the position shown in Figure 1 and will, under these circumstances, support the body of the clothes being pressed, 75 as for instance the body of a coat, while the sleeve is being pressed between the cushion and the buck.

The supporting members 23, as illustrated 80 in Figure 5, are preferably formed of a channeled rod, in other words a rod which is U-shaped in cross section, whose ends are welded together, making the support rigid.

In connection with the auxiliary table constructed as above described and for the purpose of supporting the outer margin of a trouser leg while the opposite margin is being creased, we provide a trouser leg support, designated 29. This member 29 is approximately 5" wide at one end and at the other end may be 7" wide more or less and the inner edge of this member 29 is curved; as at 30, to correspond with the curvature of the side face of the cushion. The relatively narrow end of the member 29 is braced by a cross piece 31, the inner edge of this cross piece having a downwardly projecting flange 32. This cross piece is adapted to rest upon the edge of the auxiliary table, as illustrated in Figure 2, the flange preventing shifting of this support 29. The opposite end of the support remote from the auxiliary table is supported by a downwardly extending leg 33, the upper end of which is formed with a crow foot 35, the leg 105 having screw-threaded engagement with the crow foot in a socket 35^a disposed at the intersection of the arms thereof. The lower end of the leg is formed with a transversely extending foot 36 which rests upon the main table A, permits the ready removal of the trouser leg support 29 or its ready replacement in position.

In the use of this device, when it is desired to press the legs of a pair of trousers, for instance, the auxiliary table is used and also the trouser leg support 29. The body of the garment rests upon the auxiliary table 10, while the trouser leg is disposed so that one-half of the trouser leg rests upon the cushion and the other half rests upon the support 29. Under these circumstances, a depression of the head B will press the trousers so that the crease or fold at the forward edge of the trousers will be very positively and strongly made. If the rear of the trousers leg was disposed upon the cushion, the middle of the trouser leg, that is where the seam is, would receive the greatest amount of pressure and the crease would 110 115 120 125 130

not be so pronounced. If, on the other hand, the trouser leg was disposed upon the cushion with the crease in alignment with the middle of the cushion, then the outer 5 margin of the trouser leg would hang downward and the body of the trouser leg would rest upon the table A. If the auxiliary table alone were used while the body of the trousers would be supported upon the auxiliary 10 table, the whole trouser leg would not lie flat and a good, even and proper pressure would not be produced. It is necessary, therefore, to provide both the auxiliary table and the trouser support 29 in order to 15 secure an effective and proper pressing of the legs of the trousers, particularly the crease thereof.

In pressing a coat, it is desirable that the body of the coat be supported while the 20 sleeve is disposed between the press head and cushion. The trousers support can be left in place, if desired, or removed, but with the body of the coat supported upon the auxiliary support, the sleeve is held where 25 the head will act best upon it and the weight of the coat, overcoat or like garment will not act to pull the sleeve of the garment out from between the head and cushion. In ordinary circumstances, it would be necessary 30 that the operator hold the garment up after arranging the sleeve upon the cushion or arranging the trouser leg upon the cushion so that the body of the garment will not exert any pull on the sleeve or trouser 35 leg. This is not necessary with our device, nor is there a chance for the garment to drag upon the floor and become soiled.

We do not wish to be limited to an auxiliary table made in two sections, the two sections 40 being hinged to each other for movement, as the auxiliary table might be made in one section, nor do we wish to be limited to the hinged legs or supports, nor to the particular form of these supports or the particular 45 manner of supporting the trouser leg member 29, as these parts may be varied in some respects without departing from the spirit of the invention as defined in the appended claims. The device has been found 50 very effective in actual practice, and it has been found that with this attachment all garments are more expeditiously, more completely, and more uniformly pressed than in the old way, wherein the garment is held to

hang loose over the steam pressing machine. 55 The device will enable the operator of the steam pressing machine to form a superior quality of work in a minimum of time.

We claim:—

1. In a steam pressing machine, the combination with a cushion and a main table, of an auxiliary table cut away on one end to receive the cushion and having downwardly extending legs whereby it may be mounted upon the main table of the presser, the table being formed in two sections hinged to each other and the legs being hinged to the under face of the table and foldable up against the table. 60

2. In a steam pressing mechanism, the combination with a cushion and a main table, of an auxiliary table consisting of two table sections hinged to each other for folding movement and one end of the auxiliary table being cut away upon its upper face to 75 accommodate the end of the presser cushion, a brace formed in two hinged sections, the sections being attached to the under face of the two sections of the auxiliary table adjacent said cut away portion, hinged members 80 attached at opposite ends of the table to the two sections thereof, supporting members on each side of the table hinged to said hinged members for movement into or out of parallel relation to the table, and braces 85 detachably engaging said legs and holding the legs at right angles to the table. 90

3. In a steam presser, the combination with a cushion and a main table, of an auxiliary table, the upper face of the auxiliary table at one end being cut away to receive the end of a presser cushion, means for supporting the auxiliary table upon the main table approximately on a level with the presser cushion, and a trouser supporting member adapted to coact with said cushion having a cross piece at one end adapted to rest upon one end of the auxiliary table and providing a flange normally bearing against the end of the auxiliary table and the opposite end of the trouser supporting member having a leg, the inner end edge of the trouser supporting member being curved to conform to the shape of the cushion. 95

In testimony whereof we hereunto affix 100 our signatures.

GEORGE B. COOVER.
HERBERT A. BRUNER.
